United States Patent Office

Des. 208,835
Patented Oct. 3, 1967

208,835

VTOL AIRCRAFT

Edward Kolodziej, Lake County, Ind.
(5616 W. 5th Ave., Gary, Ind. 46406)

Filed May 25, 1966, Ser. No. 2,424

Term of patent 14 years

(Cl. D71—1)

Fig. 7

FIGURE 1 is a front elevation view of the VTOL aircraft in flight embodying my new design;

FIGURE 2 is a side elevation view of my said invention;

FIGURE 3 is a plan elevation thereof;

FIGURE 4 is a rear elevation;

FIGURE 5 is a front elevation of the aircraft of my invention shown resting on the ground;

FIGURE 6 is a bottom view thereof with the wing portions broken away for convenience of illustration; and

FIGURE 7 is a perspective view of the aircraft of my invention taken from above and to the right of FIGURE 5.

I claim:

The ornamental design for a VTOL aircraft, substantially as shown and described.
